United States Patent Office

Des. 183,412
Patented Aug. 19, 1958

183,412

BABY EXERCISER OR SIMILAR ARTICLE

James M. Webster and Elmer A. Clemens, Chicago, Ill.

Application July 5, 1957, Serial No. 46,830

Term of patent 14 years

(Cl. D34—5)

Figure 1 is a perspective view of a baby exerciser or similar article, showing our new design;

Fig. 2 is a side elevational view, on an enlarged scale, the opposite side having substantially the same appearance;

Fig. 3 is a front elevational view;

Fig. 4 is a top plan view;

Fig. 5 is a rear elevational view; and

Fig. 6 is a bottom plan view thereof.

We claim:

The ornamental design for a baby exerciser or similar article, substantially as shown and described.
